UNITED STATES PATENT OFFICE.

ALBERT CLIFFORD ASPINALL, OF CHISWICK, LONDON, AND LEONARD EUGENE COWEY,
OF KEW GARDENS, ENGLAND.

TICKET-ISSUING APPARATUS.

Application filed March 18, 1926, Serial No. 95,630, and in Great Britain March 25, 1925.

This invention relates to apparatus for the issue of tickets and has particular although not exclusive reference to the issuing of tickets on omnibuses, tramway cars and other vehicles on which a conductor issues tickets during a journey.

Hitherto it has been the practice to employ tickets the colour of which vary according to the value and the conductor has to position the ticket to ensure punching at the correct fare stage whilst special types or coloured tickets are provided for such purposes as children's and workmen's fares.

The object of the present invention is to provide a light, portable apparatus for punching tickets which will obviate the wrong selection of tickets and inaccurate punching which occur frequently in using tickets of the ordinary type by enabling one type of ticket to be employed for all purposes.

According to the invention a ticket issuing apparatus is provided comprising means for punching a ticket to indicate the amount paid, independently operated means for punching to indicate the classification of ticket and further means for punching to indicate the time or distance for which the ticket is issued. According to the preferred form of the invention the apparatus comprises means for punching a ticket to indicate any one of a predetermined range of values, means for punching a ticket to indicate any one of a group of classes, means for punching a ticket to indicate the time or distance for which the ticket is issued and means for registering automatically the number of tickets issued and the number of each class and value punched.

Reference will now be made to the accompanying drawings which illustrate by way of example an apparatus constructed according to the invention and in which:

Figure 1 is a longitudinal sectional elevation looking towards the front of the machine and taken on the line 1—1 of Figure 2.

Figure 2 is a cross sectional elevation taken on the line 2—2 of Figure 1.

Figure 3 is a longitudinal sectional elevation looking towards the back of the machine with the sliding carriage, punchings tray and ticket magazine removed.

Figure 4 is a fragmentary cross sectional

elevation showing the mechanism which controls the operation of the stage punch,

Figure 5 is a plan of the machine,

Figure 6 is a plan illustrating the means by which depression of one operating key prevents depression of the remaining fare keys,

Figure 7 is a plan of an auxiliary plate which may co-operate with the plate shown in Figure 6,

Figure 8 is a plan of the plate employed for locking the class keys as one is depressed and

Figure 9 is a view showing a section of the ticket strip employed.

In the construction illustrated the tickets in the form of a fanfolded strip 1 with perforations at the folds are stored in a receptacle 2 detachably secured within a casing 3 which encloses the whole of the operating and registering mechanism. The tickets are fed from the receptacle 2 through a vertical passage 4 formed between a removable end plate 5 of the casing 3 and an inner guide plate 6, the plate 5 being hinged at 7 and normally maintained in closed position by a spring clip 8. The ticket is then fed across a die plate 9 beneath which is disposed a box 10 for punchings, such box being divided into compartments by partitions 11 which maintain separate the different classes of punchings. The punched tickets are ejected by mechanism hereinafter described through a slot 12 in the end plate 13 of the casing 3.

The preferred form of ticket used is shown in Figure 9 in which 14 indicates the fare spaces, 15 the fare stages numbered from one upwards to the number required and 16 the class spaces which in this instance are for ordinary, child's, workmen's and return tickets respectively. A ticket when issued is punched in one space of each of the three groups mentioned, the punching being effected by depressing a lever 17 for the stage, one of four keys 18 for the class and one of the series of keys 19 for the fare value, the keys 18 and 19 extending through apertures 20 in a cover plate 21 which is marked on its surface to indicate the function or value of each key or the head of each key may be so marked.

Each of the keys 18 and 19 comprises a cylindrical upper portion adapted to be

operated by hand and from which depends a 5 punching device comprising a cylindrical stem 22 whose lower end is surrounded by a sleeve 23 having a serrated lower edge 24 to ensure that a clean perforation is made. A spring 25 is disposed within the sleeve 23 which is fixed to the stem 22 so that the sleeve is depressed before a punching element 26 mounted so as to be capable 10 of independent movement in the lower end of the sleeve. The head of each key 18 or 19 is recessed as shown at 27 to accommodate a spring 28 coiled around the stem 22, the lower end of said spring bearing against 15 the horizontally extending upper end 29 of a key-lever 30. Beneath the portion 29 of the key lever is disposed a downwardly coned member 31 fixed to the stem 22. Below the members 31 is disposed a floating 20 perforated plate 32 operating in conjunction with the class keys 18 and a second and similar plate 33 operating in conjunction with the fare keys 19. One key stem 22 passes through each hole 34 in the plates 32 and 33 the function of which is to prevent depression of more than one key in either group simultaneously. The plates 32 and 33 are perforated in such a manner that when one key is depressed its coned member 31 will move the plate until a cylindrical upper portion 35 can enter a perforation, the other perforations in the plate being thereby held out of alignment with their respective keys which are thus held against effective 35 movement. The floating plates 32 and 33 are prevented from tilting and maintained in one horizontal plane by horizontal rods 36 extending above and below the plates 32 and 33 from end to end of the casing. 40 Reference to Figure 6 will explain the manner in which depression of one key locks the remaining keys against operation. When for example the key stem 22^a is depressed the conical portion 31 of the key enters the aperture 34^a and moves the plate towards the right (Figure 6) until the key stem becomes concentric with the aperture 34^a and the plate is in the position shown in broken lines in which the remaining 45 key stems are in such position relative to their respective apertures that none can be depressed until the plate is released and free for movement.

The plate 33 which surrounds the stem 50 22 of the twelve fare keys is preferably duplicated, the second plate being disposed beneath it as shown at 37 in Figure 2 so as to ensure that eleven keys are all locked against movement whenever one is depressed. 55 The lower plate is formed so that the apertures 38 therein occupy different positions relatively to the key stems than the apertures 34 and as shown in Figure 7.

The fare stage punch 39 is slidably 60 mounted in a bracket 40 carried by a screw-

threaded shaft 41 extending from end to end of the casing 3 and rotatable by means of a knurled knob 42 disposed on the shaft 41 externally of the casing to cause the bracket 40 to travel along the shaft 41 to the position requisite to punch a ticket in the correct fare space. In practice the bracket 40 is traversed through unit distance at each fare stage through which a vehicle passes, the stages being indicated to the conductor of the vehicle by a pointer 43 carried by the bracket 40 and movable in front of a scale 44 visible through a window 45 in the front of the casing 3. The bracket 40 and pointer 43 are formed preferably in one piece which is 70 prevented from rocking around the shaft 41 as a pivot and maintained in the correct vertical position by means of a horizontal guide rod 46 engaging a groove 47 in the underside of the bracket 40. The stage 75 punch 39 is formed with a mushroom head 48 engaged by a groove 49 in an elongated arm 50 which extends from end to end of the casing in order to engage and depress the stage punch in any position to which it may 80 have been adjusted along the shaft 41, the said arm 50 being normally maintained in the inoperative position shown in Figure 2 by means of a spring 51 which returns it to such position after operation. The arm 85 50 is carried by a spindle 52 which projects through the end of the casing above the removable portion 5 and carries the operating lever 17. The knob 42 by which the screw 90 threaded shaft 41 is rotated abuts on its inner face against a boss 53 formed on the end 13 of the casing said boss being formed with a socket 54 in which is disposed a spring 55 pressing on a ball 56 adapted to engage a recess 57 formed in the inner face 95 of the knob 42, the strength of the spring being such that the operator can rotate the knob 42 freely, the ball engaging the recess 57 once during each revolution offers sufficient resistance to indicate to the operator 100 that the bracket 40 is in the correct position for punching in one of the stage indicating spaces of a ticket.

The stage punch mechanism also embodies 105 means for preventing punching at half stage intervals and for preventing the shaft 41 from being rotated when the punch 39 is being operated. These locking means comprise a spur wheel 58 on the screw-threaded 110 shaft 41 meshing with a second gear which carries a disc 59 slotted at 60 and adapted to be engaged when in the position shown in Figure 4 by a tooth 61 formed on an arm 62 mounted on the operating spindle 52. The arm 62 is normally held inoperative by 115 a trigger 63 which has a recess 64 engaging the shaft 41 and is normally maintained in the position shown by a leaf spring 65 mounted on a fixed portion of the framework of the machine. The lower portion 120

125 130

of the trigger is engaged by a tapered cam 66 mounted on a slideable carriage as hereinafter described and operation of which rocks the trigger about the shaft 41 against the action of its spring. The arm 62 and operating lever 17 are then free to be moved downwards to operate the stage punch when the slot 60 is in the position shown in Figure 4.

16 All of the punches are normally held inoperative by means of a perforated die plate 67, the perforations in which lie normally out of alignment with the punch elements, said die plate forming part of a slideable carriage 68, the underside of which is provided with means hereinafter described to engage a rackbar 69 formed in the base 70 on which rests the receptacle 10 and having three sets of teeth 71, 72 and 73 formed therein. When the apparatus is to be freed for operation a knob 74 on a stem 75 connected to the carriage 68 and passing through a gland 76 in the wall 13 of the casing is pushed inwardly and the carriage is held temporarily in the adjusted position, by pawls 77 and 78 mounted respectively on spindles 79 and 80 mounted in the underpart of the carriage and extending at right angles to the direction of travel of the carriage 68.

30 The carriage 68 is formed with inturned lugs 81 which engage a pair of horizontal rods 82 on which the carriage slides and the carriage is formed with a transverse end portion 83 to which the stem 75 is connected by means of nuts 84. To the end of the carriage 68 remote from the stem 75 is secured a second stem 85 projecting through the wall of the casing and having a knob 86 for manual operation, this stem being used for returning the carriage to normal position after the machine has been used for a cycle of punching operations. The double pawl mounted on the spindle 80 comprises a pawl 78 fixed to the spindle and a second pawl 87 loosely mounted on the spindle. The loose pawl 87 is normally held down by a member 88 extending from the spindle 80 and when the spindle is rocked as herein-after described the pawl 87 is moved upwardly by a spring 89 bearing on the pawl from below and into engagement with the rack teeth 72. Rocking of the spindle 80 removes the pawl 78 which is fast on the spindle 80 from engagement with the rack teeth 73 and by tending to straighten the spring 89 assists in forcing the pawl 87 upwards. In the normal position, however, the pawl 78 occupies the position shown in Figure 3 in which it engages the rack teeth 73 and prevents any accidental vibratory movements of the carriage which might tend to operate incorrectly the totalizing counter hereinafter described.

The ticket strip which passes up the passage 4 next passes through a passage 90

formed between the fixed die plate 9 and the movable die plate 67 which carries a post 91 to which is pivoted a lever 92 one end 93 which is bent so as to be capable of engaging slots 94 and 95 formed respectively in the die plates 67 and 9, the said lever normally resting on the upper surface of the ticket strip, but engaging the slot 95 when no strip is present in the passage 90 under the influence of a spring 96 fixed to the die plate 67. The opposite end of the lever 92 is formed with notches 97 adapted when no strip is present to engage a fixed stop 98 and prevent movement of the carriage 68.

To enable an ejected ticket to be torn from the strip a claw is provided which comprises a plate 99 having a downwardly extending portion 100 having a serrated lower edge normally resting on the plate 9. The plate 99 has a downwardly extending portion 101 at its inner end mounted upon a fixed pivot 102 around which it is rotated slightly when the carriage is moved to operative position by the action of a cam 104 which engages beneath a member 103 connected to the plate 99 to raise the latter at its outer end and remove the claw from the path of the ticket strip. When the carriage is restored to normal position the claw falls on to the surface of a ticket and as the ticket is withdrawn eventually engages in the perforations 105 between the first and second tickets enabling the first ticket to be torn away.

When the carriage 68 is moved into operative position the ticket strip is held in place by a sprag 106 mounted on a pivot 107 carried by a fixed guide plate 108. The surface of the ticket is also engaged by a second sprag 109 mounted on a pivot 110 carried in a bearing plate 111 extending upwards from the carriage 68, this sprag being pressed downwardly by a spring 112 and serving to move the ticket strip forward during the return of the carriage to normal position until one end of the ticket projects through the slot 12. To prevent slight movements of the carriage within the scope of the rack teeth 73 operating to advance the ticket strip out of correct alignment with the punching dies, the sprag 109 is provided with a lost motion device comprising a slot 113 in which the pivot pin 110 engages so that the pivot must engage that end of the slot 113 which is further from the casing wall 13 before any movement of the ticket strip can commence. The sprags 106 and 109 extend through slots 114 and 115 respectively in the plate 67.

The mechanism will now be described whereby the operation of the various punches is transmitted to registering mechanism disposed in the base of the machine. The key levers 30 extend downwards against the back of the machine casing and are formed on their forward edges each with

a detent 116 and at a lower point with rack teeth 117. At a still lower point is formed a hook 118 to which is attached the lower end of a tension spring 119 the upper end of which is attached to a fixed hook 120, the said spring being extended when a key is depressed and serving to restore the key lever and key to normal position at the conclusion of one cycle of operations. The lower ends 10 of the key levers 30 are bent into horizontal portions 121 which are slideable vertically in slots 122 formed in a fixed guide plate 123. From each horizontal member 121 depends a spring finger 124 which engages the unit 15 wheel of a counter 125 rotated through the space of one unit at each depression of a class or fare key, there being one counter for each class and fare key so that independent registers are kept by the machine 20 of the number of tickets issued of each value and of each class. The detents 116 of the key levers 30 are adapted when the keys are depressed to engage and depress plates 126 and 127, the former being operated 25 by the class keys and the latter by the fare keys, the plates being slideable vertically in guides 128 and having inclined slots 129 engaged by studs 130 projecting forwardly from the rear casing wall. The studs 130 30 limit the amount of movement which can be imparted to the plates 126 and 127 which owing to the disposition of the slots 129 move downwardly and towards the right (Figure 3) when operated but are maintained normally in the position shown by 35 springs 131 bearing against upwardly extending end portions 132 and 133 of the plates. The lower edge of the plate 126 is adapted to engage an arm 134 fixed to the 40 pawl spindle 79 and the lower edge of the plate 127 is adapted to engage an arm 135 fast on the pawl spindle 80.

Under the carriage 68 a catch plate 136 for the class key levers and a longer catch 45 plate 137 for the fare key levers are pivoted on one of the rods 82. The lower edges of these plates are formed with the teeth 138 which in the normal position lie between the key levers 30. When, however, the carriage 68 is moved prior to operation of the 50 punches the teeth 138 are brought into alignment with the key levers so that when one of the key levers is depressed a tooth 138 engages one of the rack teeth 117 and prevents restoration of the key lever and punch to 55 normal position until the carriage is restored to normal position at the conclusion of a cycle of operations. In this manner depression of any punch twice on one ticket 60 is prevented. The catch plates 136 and 137 are held in operative position by the action of springs 139.

The catch plates are moved from the 65 inoperative position shown in Figure 3 to a position in which each tooth rests on a key

lever by means of a member 140 projecting at one end of the carriage and which having to travel idly for some distance before engaging the catch plates ensures that the catch plates are only moved just the distance 70 sufficient to bring their teeth into positions of potential operation. On the return movement of the carriage the catch plate is released during the last portion of the travel there being a lost motion action 75 between the carriage and the catch plates 136, 137.

Means are provided to register the total 80 number of tickets punched by the machine or in other words the number of times the carriage 68 is moved to and from operative position. These means comprise a roller 142 extending outwardly from one end of the carriage 68 which engages a slot 141 at one end of a bell crank lever 143 mounted 85 on a fixed pivot 144, the other arm of said bell crank lever engaging a slot 145 in a lever 146 the lower portion of which is constructed similarly to the lower portions of the levers 30 and operates an independent 90 counter mounted with the counters 125 in a tray in the base of the machine.

The counting devices employed may be of 95 any suitable construction and are provided each with a ratchet wheel 147 engaged by the arm 124 when a key lever is depressed, and with a spur wheel 148 engaging a spur pinion 149 engaged by a spring detent 150 to prevent unintentional rotation of the 100 counter.

The base of the machine is formed in two parts, the first of which a tray 151 has upwardly extending edges 152 which engage 105 between the walls of the casing 3 and the sides of a framework 153 in which the counter spindles 154 are mounted, this framework being first secured in place by means of screws 155 which engage bosses 156 projecting inwardly near the lower ends of the casing walls 3, the heads of the screws being accessible only when a lock 157 has been turned and the tray 151 withdrawn. The machine is so arranged that unlocking 110 of the tray 151 by inserting and turning a key in the lock 157 frees all parts of the machine for removal or adjustment as the case may be. Bearing upon the tray 151 is a lever 158 secured to the end wall 6 of the casing by means of screws 159 which pass through slots 160 in the lever, the upper 115 end of which has an upwardly projecting arm 161 adapted to engage in front of a pin 162 projecting downwardly from the base of the confetti tray 10 and prevent removal of the latter. When the tray 151 is removed however, the lever 158 can move 120 downwardly within the limit allowed by the slots 160 under the influence of a spring 163 mounted at one end on a screw 164 fixed to the casing wall 6 and bearing at its free 125 end.

129

end on a projecting portion 165 of the lever 158. Thus when the tray 151 is removed the confetti tray is released automatically for withdrawal which is effected by pressing 5 upon a stud 166 projecting through the wall 13 of the casing.

The upper ends of the screws 155 which secure the counter framework 153 in place also engage notches formed in plates 167 10 extending laterally from the front plate of the casing, normally preventing removal thereof. When the tray 151 has been removed, the screws 155 may be slackened and the front plate removed permitting access 15 to a spring 168 projecting from the top of the ticket magazine 2 and normally preventing withdrawal thereof by engagement with the inner face of the wall 6 of the casing.

The lock 157 includes a spindle 169 terminating at its upper end in a catch 170 adapted when in the locked position to engage a horizontal portion 171 of the fixed guide plate 123. Turning of the member 169 to inoperative position by insertion of the key 20 thus allows the tray 151 to be completely removed at the end of a journey for examination and resetting of the counters. The base of the tray 151 is pierced with eight openings 172 which are protected by a sheet 25 of glass or other transparent material 173 maintained in position by a cover plate 174 also provided with eight openings 175 and sprung into position by causing projections 176 formed on its upturned ends 177 to engage in depressions 178 formed in the end walls of the casing.

The operation of the machine above described is as follows:—

The fan folded ticket strip having been 40 placed within the magazine 2 the foremost ticket is brought by hand up the channel 4 and inserted in the trough or passage 90 where it is held in operative position by the member 93 and sprag 106. The casing member 5 is then closed and the counter tray 45 locked in place when the machine is ready for use, the counters having been zeroized or their totals noted.

When it is desired to issue a ticket, the 50 key 74 is pushed inwardly moving the carriage 68 towards the right, Figure 1, and positioning the movable die plate 67 so that the fare and stage keys are free to be operated. The carriage 68 becomes locked in 55 its adjusted position by engagement of the pawls 77 and 78 with their respective racks in the bar 69. The movement of the carriage also rocks the bell crank lever 143 so that the total counter is progressed one 60 unit and by means of the cam 66 removes the trigger 63 from the path of the pawl 62 so that the stage punch is freed for operation. The stage punch bracket is progressed through unit distance by the conductor turning 65 the knob 42 through one revolution at

the completion of each fare stage of the journey.

One of the fare keys 19 is next depressed causing the ticket to be punched in the appropriate fare space and a lever 30 to be 70 depressed to operate its counter and to be locked in depressed position by the catch plate 137. The plate 127 is also depressed rocking the pawl spindle 80 in a clockwise direction, Figure 3, disengaging the pawl 78 75 and causing the pawl 87 to engage the rack teeth 72.

One of the class keys is next depressed causing punching of the ticket in the appropriate class space, operation of its counter, locking of a key lever 30 by the catch plate 136 and release of the pawl 77 from the rack 71 so that the carriage is now held only by the pawl 87. After operation the fare and class keys are held in depressed 80 position by the catch plates 137 and 136 to prevent a ticket being punched in more than one fare space and class space.

Depression of the lever 17 and operation of the stage punch 39 completes the punching of the ticket and the key 86 is pushed inwardly to restore the slideable carriage 68 to normal position. When the key 86 is pushed inwardly the pawl 87 is forced out of engagement with the teeth 72 against the action of the spring 89 by the movement of the carriage 68. This movement shifts the movable die plate 67 to locking position and allows the spring 65 to restore the trigger 63 to a position in which the stage punch 39 100 is locked. During this reverse movement of the carriage the sprag 109 pushes the ticket strip forward until its end projects through the slot 12 where it can be grasped and pulled outwardly until its progress is arrested by the claw 100 engaging a row of perforations 105 when the ticket can be torn away.

We claim—

1. A ticket issuing apparatus comprising a number of punching elements each corresponding to one of a predetermined range of values, a number of punching elements each corresponding to one of a group of classes, a single punching element adapted to be progressed a certain distance across the machine at each stage of a journey or the like to alter its position relatively to the ticket, means for releasing said punching elements for operation, means for preventing depression of more than one punch in each of the value and class groups, and means for registering the number of operations of each punch and the total number of tickets issued. 110

2. A ticket issuing apparatus comprising a group of value punches, a group of class punches, a stage punch, means for feeding a perforated ticket strip beneath the punch, a slideable carriage adapted when moved to operative position to release all the punches 115 120 125 129

for operation, means for preventing more than one value punch and one class punch in any one ticket, means for registering separately the operations of the several punches and the tickets issued and means for partially ejecting a ticket as the carriage is returned to its locking position at the completion of a cycle of operations.

3. A ticket issuing apparatus, including 10 value and class punches, a slideable carriage controlling the engagement of said punches with the ticket, key levers operably connected with said punches, counting devices actuated by said levers and means for holding 15 said key levers, in depressed position until the return of said carriage to normal position.

4. A ticket issuing apparatus, including 20 class and value keys, a slideable carriage, and a pair of pawls temporarily locking said carriage in operative position, said pawls being 25 disengaged respectively by depression of a class and a value key to free said carriage for return to normal position and for partially ejecting a ticket at the end of a cycle of punching operations.

5. A ticket issuing apparatus, as set forth 30 in claim 3, including catch plates pivoted on said carriage and adapted to engage teeth formed on said key levers upon the latter being depressed.

6. In a ticket issuing apparatus, a screw 35 threaded shaft extending across the machine, a stage punching device adapted to be traversed along said shaft, means for indicating the completion of movement from one punching position to another, and means for permitting depression of the punch only in correct position relative to spaces provided on 40 each ticket.

7. A ticket issuing apparatus, including

a removable ticket magazine, a removable partitioned tray for collecting punchings from the tickets, a counter device, and a tray carrying said counter device and adapted to 45 be locked in the base of the machine, unlocking of said tray permitting the withdrawal of said ticket magazine and said partitioned tray.

8. A ticket issuing apparatus, including 50 punching elements, a slideable carriage having a movable die plate controlling the engagement of said punches with the ticket, ticket operated means for releasing said carriage for movement to permit engagement of 55 said punches with the ticket, a pawl carried by said carriage and bearing upon the surface of the ticket to force the latter through a delivery slot during return of said carriage to normal position and means for holding 60 the ticket strip for severing a portion thereof at a perforated line.

9. A ticket issuing apparatus, including 65 punching elements, a slideable carriage having a movable die plate controlling the engagement of said punches with the ticket, ticket operated means for releasing said carriage for movement to permit engagement of 70 said punches with the ticket, means for preventing movement of the unpunched ticket upon movement of said carriage to operative position.

10. In a ticket issuing apparatus, a stage 75 punch, value and class punches, a slideable carriage controlling the engagement of said value and class punches with the ticket, and means including a cam releasing said stage punch for operation during the movement of said carriage to operative position.

In witness whereof we affix our signatures.

ALBERT CLIFFORD ASPINALL.
LEONARD EUGENE COWEY.
